(57) **CLAIM**

The ornamental design for a float switch housing, as shown and described.

DESCRIPTION

FIG. 1 is a front perspective view of a float switch housing showing an embodiment of the new design;

FIG. 2 is a front view of the embodiment shown in FIG. 1; FIG. 3 is a rear view of the embodiment shown in FIG. 1; FIG. 4 is a first side view of the embodiment shown in FIG. 1;

FIG. 5 is a second side view of the embodiment shown in FIG. 1;

FIG. 6 is a top view of the embodiment shown in FIG. 1; and, FIG. 7 is a bottom view of the embodiment shown in FIG. 1.

The broken lines in the drawings illustrate environmental structure of the float switch housing that form no part of the claimed design.
